(57) **CLAIM**

The ornamental design for a winged scale, as shown and described.

DESCRIPTION

FIG. 1 is a front left perspective view of an exemplary winged scale according to a closed-position embodiment of

the present invention, having a digital display depicted in phantom and left and right wings folded in a closed position on a topside.

FIG. 2 is a top plan view of the winged scale of FIG. 1.

FIG. 3 is a front elevational view of the winged scale of FIG. 1.

FIG. 4 is a back elevational view of the winged scale of FIG. 1.

FIG. 5 is a left side elevational view of the winged scale of FIG. 1, the right side elevational view being a mirror image.

FIG. 6 is a bottom plan view of the winged scale of FIG. 1.

FIG. 7 is a front left perspective view of another exemplary winged scale according to an open-position embodiment of the present invention, having a digital display depicted in phantom and left and right wings unfolded in an open position.

FIG. 8 is a top plan view of the winged scale of FIG. 7.

FIG. 9 is a front elevational view of the winged scale of FIG. 7.

FIG. 10 is a back elevational view of the winged scale of FIG. 7.

FIG. 11 is a left side elevational view of the winged scale of FIG. 7, the right side elevational view being a mirror image; and,

FIG. 12 is a bottom plan view of the winged scale of FIG. 7.

The broken line showing is for illustrative purposes only and forms no part of the claimed design.
